ERNEST H. COOK, OF PAINESVILLE, OHIO, ASSIGNOR OF ONE-HALF TO ALBERT LYNN
LAWRENCE, OF CLEVELAND, OHIO.

BRUSH-CLEANING DEVICE.

1,285,948.

Specification of Letters Patent. Patented Nov. 26, 1918.

Application filed March 7, 1916. Serial No. 82,658.

To all whom it may concern:

Be it known that I, ERNEST H. COOK, a citizen of the United States of America, residing at Painesville, in the county of Lake 5 and State of Ohio, have invented certain new and useful Improvements in Brush-Cleaning Devices, of which the following is a specification.

My invention relates to improvements in a 10 brush cleaning device, and has for its object, the provision of means for efficiently and economically cleaning paint brushes that have become soaked and coated with dried paint, varnish, shellac and the like.

15 It is well known that all paint shops are compelled either to use brushes which are of impaired efficiency, by reason of the old paint forced into the heel of the brush, or to throw said brushes away. The one course 20 involves loss in efficiency of the workman, while the other compels the purchase of a new brush to replace the one disposed of. These losses or wastes, however, are wholly unnecessary, provided the old brushes may be 25 restored substantially to their normal efficiency, and it is common practice to soak the brushes in turpentine, varnish remover and the like, in order to clean them, more or less thoroughly. The cost of the material, however, which is wholly wasted, under ordinary 30 conditions, greatly reduces the effect of this attempted economy.

Accordingly, I have devised improved means for thoroughly cleaning paint brushes 35 and the like, with minimum expenditure of labor and material, and in addition, I am enabled to reclaim oil and paint material from the brushes in such quantities, as commonly will far exceed the cost of the solvent 40 used.

Preferably, my improved apparatus provides a sealed chamber for containing the solvent, which places the vapors thereof, under moderate pressures, and practically 45 avoids evaporation, in addition to apparently effecting increased penetrative power for the solvent employed. The apparatus further provides a suitably perforated diaphragm or grating, which may be used with advantage 50 for working out the inner body of hardened paint, while preventing the disturbance of the solvent liquid, and the separated or reclaimed ingredients of the paint. Moreover, I provide an appliance for combing out the 55 particles of softened paint, and for scraping

the skins of paint surrounding the bristles of the brush, into the brush.

The device of my invention is of extreme simplicity; providing a liquid seal for the inclosing closure, an inner containing receptacle for the solvent, and a tray affording a diaphragm at its bottom; in which tray, said brushes are disposed while under treatment.

Further features of my improvement will be explained in connection with the accompanying drawings, wherein:—

Figure 1 is a view in longitudinal section of a device embodying my invention.

Fig. 2 is a transverse sectional view thereof.

Fig. 3 is an end view partially broken away, and in section, and

Fig. 4 is a plan view of the device, with the cover removed.

Throughout the several figures of the drawings I have employed the same character of reference to indicate similar parts, and the dotted section lines are suitably indicated by corresponding ordinals, to assist in locating said figures.

A liquid containing tray *a*, of the desired 80 dimensions, and constructed advantageously of galvanized iron, as are the remaining members of my improved device, is adapted to receive the air-tight cover or closure *b*. These members telescope, fitting loosely one 85 within the other, and a liquid or water-seal is provided therebetween. Fig. 1 shows the cover *b* lowered into sealing position; the parts being so proportioned and related, that normally the outer water-level in *a* will be 90 higher than that beneath the closure *b*, when properly sustained by the liquid. Within the closure, and resting upon the bottom of the tray, there is provided a receptacle *c*, adapted to receive the liquid solvent. This 95 receptacle advantageously may be initially filled with such suitable solvent as it is desired to use, of which I may suggest a mixture comprising two parts of benzol and one part of denatured alcohol. An open bottomed 100 tray *d*, is adapted to rest upon the rim of the receptacle *c*; said tray being provided with a crosspiece *d'*, adapted centrally to support the diaphragm *e*, of netting, clamped and riveted into a stout supporting frame *e'*. 105

At one end of the inner tray *e*, there is provided a scraper or blade *f*, while at the other end of the tray, I may advantageously dispose a comb appliance *g*. Both of these mechanically cleaning elements or members, 110

preferably are so positioned, that the material removed from the brushes shall fall within the liquid solvent. Two of such brushes *h* and *i*, are shown in Fig. 1; the 5 former in such position that a large number of the brushes may be piled one on top of the other, across the tray, and in Figs. 2 and 4, one brush only is indicated. It will be understood, however, that the tray may be 10 filled to its capacity, and that the device itself may be made of such dimensions and shape as will be best adapted to any particular workshop.

With an understanding of the device 15 shown, I may now explain the use thereof. Assuming that the inner tray has been filled with all brushes that are to be cleaned, it is necessary to insure merely that the bristles of the brushes will rest upon the grating, so 20 that the solvent liquid will penetrate said bristles, and be carried by capillary action into the paint soaked heels. The closure *b*, is then placed over the receptacle, and within the outer tray, so that a liquid seal is insured, which brings about two desirable results. First, the volatile solvent is prevented 25 from evaporating into the air, while the contained vapor within the cover is placed under certain pressure, depending, of course, upon the weight of the cover. My observation 30 leads me to believe that this penetrative action of the vapor is highly beneficial in disintegrating the hardened and dried paint, and materially assists the action of the liquid solvent in reducing the ingredients thereof.

After the brushes have remained some twenty-four hours or more within the device, the cover *b*, may be removed, and each brush in turn, may be worked by rotating motion 40 upon the grating; first scraping off any particles of skin from the outer portion of the bristles, and combing out the inner portions of hardened paint from time to time, until the heel of the brush itself has been freed 45 from all particles of paint. This will be accomplished with surprising ease, inasmuch as the solvent has every opportunity to attack the foreign material, throughout the body of the bristles, without in the least, impairing their original efficiency. Thus a 50 material advantage is insured at the outset, by involving very little labor for restoring the brushes to a condition for most advantageous use.

55 Turning to the other phase of the economy, it is of importance to note that the liquid solvent is prevented from evaporating in any material volume, while the diaphragm avoids disturbing all but the upper level thereof, during the cleaning operation. Said liquid solvent, of course, may be added to from time to time, until the efficiency of the body is decreased by the reclaimed materials. These materials comprise a solid disintegrated portion *j*, of the paint material, which

being heavy will sink to the bottom of the receptacle *c*. Over this will be found a stratum of heavy oil *k*, while the liquid solvent *l*, being of less specific gravity, will rest upon the oil, and its level will be maintained 70 of sufficient height to extend some distance through the grating *e*, when the tray *d*, is inserted within the receptacle.

After the device has been used for some time, it of course, will require cleansing. 75 First, the body of expended solvent may be poured off, then the heavy oil will be decanted, and subsequently used to treat roofing shingles and the like. Finally, the body of disintegrated paint, which will be found to 80 have a grayish or dove color, may be suitably mixed and used as a paint for the floors of porches and the like, as it is slightly gritty in character, which well adapts it to this and analogous purposes. These materials 85 are all reclaimed in the course of cleaning out the device, and restoring it to condition for use, and the value of said materials, in consequence, will off-set the cost of the liquid solvent used. Inasmuch as the device is so 90 constructed that all cleaning operations are conducted within the supporting tray, the materials are all conserved. No waste of liquid solvent occurs, other than the slight evaporation, during the mechanical cleaning 95 operations, and every possible economy is attained.

In order to reclaim all of the ingredients, while making the device self-contained, it is quite desirable that the supporting tray 100 shall have associated with it, suitable abrading means, in addition to the netting, for mechanically removing the particles of disintegrated paint. Being thus positioned, all of such material will fall through the 105 bottom of the tray into the receptacle. For this purpose, I have provided the blade *f*, and comb *g*, which are suitably positioned for most convenient use, and for saving all particles of the disintegrated paint. However, these and other details are subject to 110 variation, without departing from the spirit of my invention.

It will be understood that the containing tray ordinarily will be partly filled with 115 water, which insures the practical elimination of danger from fire, ordinarily attendant upon the presence of bodies of solvent, turpentine, varnish remover etc. This is an important advantage that is inherent in 120 the device set forth.

Having now described apparatus embodying my invention, and the manner in which the same may be used, I claim as new, and desire to secure by Letters Patent, the following:—

1. In apparatus of the class described, the combination with a receptacle adapted to contain a liquid solvent, of a shallower tray having an open grating covered bottom sec- 130

- tion adapted for insertion within said receptacle, and means for effecting a substantially air-tight seal for said tray and receptacle, substantially as set forth.
- 5 2. In apparatus of the class described, the combination with a receptacle adapted to contain a liquid solvent, of a shallower tray having an open grating covered bottom section adapted for insertion within said receptacle, an abrading appliance positioned adjacent to said grating, and means for effecting a substantially air-tight seal for said tray and receptacle, substantially as set forth.
- 10 3. In a device of the class described, the combination with a receptacle adapted to contain a volatile liquid solvent, of supporting means provided in the upper portion thereof, a surrounding tray adapted to contain a liquid sealing medium, and a telescoping closure member proportioned to be floated upon said liquid sealing medium and adapted to maintain the volatile liquid and vapors under pressure, substantially as set forth.
- 15 4. In a device for cleaning paint brushes, the combination with a receptacle, of a shallower tray adapted for insertion within said receptacle, and having a grating covered bottom section, and a plurality of abrading or combing points positioned adjacent to said section, whereby the material loosened or combed thereby, may be released in position to fall through the bottom section and into the receptacle, substantially as set forth.
- 20 5. In a device for cleaning brushes, the combination with a relatively deep recep-
- tacle, of a tray adapted for insertion within the upper portion of said receptacle; said tray being provided with a netting or grating along its bottom section, adapted to form a division wall or diaphragm in the receptacle, abrading means positioned adjacent to said grating, and closure means for effecting a substantially air-tight seal about the 40 receptacle, substantially as set forth.
- 25 6. In a device for cleaning brushes, the combination with a relatively deep receptacle, of a tray adapted for insertion within the upper portion of said receptacle; said tray being provided with a netting or grating along its bottom section adapted to form a division wall or diaphragm in the receptacle, abrading means positioned adjacent to said grating, and an air tight closure member 50 surrounding said receptacle and tray, loosely telescoping within and adapted to be sustained by a water-seal to maintain the contents under pressure, substantially as set forth.
- 30 7. In a device for cleaning brushes and the like, the combination with a solvent receptacle, of a perforated diaphragm positioned therein, abrading means disposed adjacent to said diaphragm within said receptacle, a cover normally closing the device, and liquid sealing means, substantially as set forth.
- 35 In testimony whereof I do now affix my signature in the presence of two witnesses.
